HINGE FOR DOORS

Jack Shamroth, Bristol, Conn., assignor to Bowser,
Technical Refrigeration, division of Bowser,
Inc., Terryville, Conn., a corporation of Indiana

Application April 26, 1952, Serial No. 284,531

3 Claims. (Cl. 16—131)

1

This invention relates to door mountings, and more particularly to a mounting which permits a heavy door not only to swing pivotally relative to a cabinet but also permits the door to move laterally toward the cabinet opening so that an equalized sealing pressure may be applied around the perimeter of said door.

An object of the invention is to provide a door mounting of an especially strong structure which supports a heavy door and permits it to swing 10 pivotally away from the face of a cabinet opening, and which has a special arrangement for permitting the door to part from and approach the cabinet in a non-pivotal manner. This arrangement is particularly requisite in the structure of modern temperature and humidity and pressure cabinets where a uniform seal must be maintained around the whole sealing area of the door against the cabinet opening.

Also, this novel arrangement prevents the 20 gasket seal on the door or cabinet from being worn unevenly as would occur with other conventional forms of door mountings or hinges.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, 30 will best be understood by reference to the specification and accompanying drawings, in which:

Figure 1 is a perspective view of the hinge mounting embodying the novel features of my invention;

Fig. 2 is a side view, partly in section and partly broken away, taken on line 2—2 of Fig. 1;

Fig. 3 is a front elevation of a temperature and humidity cabinet showing a door suspended on the door mounting and latched to the cabinet;

Fig. 4 is a top section view, partly broken away and greatly enlarged, taken on line 4—4 of Fig. 3;

Fig. 5 is a side view showing the latch mechanism for maintaining the door closed upon the cabinet.

When various types of products, industrial equipment and instruments are to be tested in a cabinet to determine their properties under different atmospheric and environmental conditions, the factors of temperature, pressure and humidity, and the like, must be carefully controlled within precise and narrow limits. In order to maintain these conditions in such a cabinet within such limits, it is necessary to provide a

2

very heavy door to serve as a closure for the opening in the cabinet to prevent any appreciable losses from the interior of the cabinet. Also the door must be urged against the cabinet in such a manner that there is substantially equal pressure on all areas of the gasket seal, while at the same time no excessive wear is incurred on any part of the gasket due to opening and closing the door as would obtain with conventional hinge mountings. With conventional mountings where the pivot point is fixed, usually considerably more pressure is applied upon the gasket near the pivotal axis than is applied at the opposite ends of the door.

It is desirable, therefore, to provide a hinge mounting which produces no greater pressure upon the gasket seal at and near the pivotal axis than at the opposite end of the door. Hence, the present invention comprises a loosely articulated hinge mounting which permits the door to move away from as well as approach the chamber opening laterally without reference to a pivotal axis, and yet will permit the door to swing pivotally away from the cabinet and be supported by the mounting which is especially designed to sustain the type of heavy door required for such cabinets.

Referring now to the drawings in detail, Figs. 3 and 4 show a cabinet 11 mounted on a base 12 and having a door 13 covering the chamber opening 15. Fastened around the inner face of the door is a gasket 16 made of rubber or other suitable resilient material which is arranged to surround the opening of the chamber and to form a seal between said door and said cabinet. Alternatively, the gasket may be connected to the face of the cabinet around the chamber opening instead of to the door while in some embodiments, two or more gaskets spaced apart from each other may be arranged to seal off the chamber.

Door 13 is pivotally hinged to chamber 11 by means of a hinge mounting generally designated 17 as shown in Fig. 1. One portion of said mounting is attached to the cabinet by means of plate 18 bolted to the front face of said cabinet. Forwardly extending upper plate 19 and lower plate 20 are welded or otherwise connected to plate 18 which may have suitable recesses to accommodate the rear edges of said plates. Upper gussets 21 and lower gussets 22 of a generally triangular shape are welded or otherwise connected in pairs between plates 18, 19, and 18, 20, to provide supporting strength for plates 19 and 20, respectively.

Inserted through apertures in plates 19 and 20 is a vertical shaft 24 which may have a suitable flanged cap at its upper end which supports shaft

24 in position. Shaft 24 may be freely removable upward from plates 19 and 20, or it may be permanently fixed in said plates as desired. A seamless tube 25 surrounds and rotates vertically around shaft 24.

In some embodiments, thrust bearings, generally designated 26 and 27, may be interposed between tube 25 and plates 19 and 20, respectively, to minimise rotational friction, while in other embodiments, tube 25 may extend to plates 19 and 20, the thrust bearings being omitted. Welded or otherwise connected to tube 25 is an outwardly horizontally extending shaft 28, tube 25 having a suitable recess to accommodate the rearward portion of shaft 28. If desired, tube 25 may be dispensed with and shaft 28 may be connected directly to shaft 24 which would rotate within plates 19 and 20.

Although members 24 and 28 are illustrated in Fig. 2 as being hollow, said elements may alternatively be of solid construction.

The door portion of the mounting comprises bracket 29 bolted or otherwise attached to the side edge of door 13 and having two perpendicular ears 31 and 32 extending in parallel vertical planes. Said ears have apertures 33 and 34 respectively, through which shaft 28 slidably extends. Encircling pin 28 is a shaft collar 35 between ears 31 and 32 of bracket 29. Collar 35 has an aperture 36 accommodating a set screw for fixing collar 35 in position on shaft 28.

It will be seen that door 13 is movable laterally relative to the mounting on cabinet 11 by virtue of ears 31 and 32 extending longitudinally on shaft 28. In order to prevent said ears from moving too far outward on shaft 28, collar 35 is secured and fixed in position by tightening set screw 37 in aperture 36, the lower end of said set screw (not shown), impinging upon and engaging shaft 28. Hence the outer motion of door 13 from cabinet 11 is limited while at the same time sufficient clearance is given to permit gasket 16 to move away from the chamber opening.

Although door 13 swings pivotally upon pin 24, the region of said door closest to the vertical axis of shaft 24 is movable laterally relative to the face of chamber 11 and the chamber opening 15. Hence, when door 13 is swung into position opposite chamber opening 15, said door may then be urged against chamber 11 with equal pressure being exerted upon all areas of said door, and consequently, an even pressure is exerted upon all parts of the gasket 16, thus ensuring an even seal around the chamber opening and ensuring even wear upon said gasket.

Door 13 is secured to cabinet 11 by means of latch mechanisms on both sides of said door. Although two latches, generally designated 38, are shown, one on each side of said door, in some embodiments where especially heavy and large doors are involved, more than one latch may be provided for each side of the door.

The latch mechanism 38 comprises a bracket 41 bolted or otherwise secured to the face of the cabinet. Horizontally extending connecting strips 42 are pivotally connected to said bracket by means of a hinge pin 43 positioned in a forwardly extending hinge post 44 on bracket 41. Connected between connecting strips 42 is a bar 45 to the inner end of which is connected the bolt 46 which is adjustably threadable into nut 47 connected to said bar. Bar 45 has a recess, not shown, adapted to accommodate the end of bolt 46. Pivotally connected to bar 45 is a handle 48, which is normally in the lowered position as

shown in Figs. 3 and 5. Said handle 48 is liftable to extend in a straight line with connecting strips 42 to provide increased leverage for the latch when it is brought into play to close the door upon the cabinet.

Bolted or otherwise connected to the side edges of door 13 is a plate 49 to which is connected a cam plate 51 having an outwardly extending cam 52. A curved cam surface 53 on the forward edge 10 of cam 52 is engageable by the head of bolt 46 when latch 38 is swung around to secure door 13 to cabinet 11. It will be noted that bolt 46 may be adjusted inwardly or outwardly in order to provide the appropriate pressure upon gasket 16. 15 Should gasket 16 undergo some wear or lose some of its resiliency, bolt 46 may be adjusted to press upon the cam 52 to urge door 13 closer to cabinet 11, thereby bringing greater pressure on gasket 16.

When latches 38 are swung outwardly to release door 13, said door may move laterally away from the face of cabinet 11, since ears 31 and 32 of bracket 29 move outwardly longitudinally upon the shaft 28, after which the door may be swung pivotally on hinge 17. Conversely, when the door 25 is to be closed, it moves pivotally towards cabinet 11 to face the chamber opening 15. The door 30 is then pressed toward the chamber opening 15, this movement being permitted by the arrangement of ears 31 and 32 moving inwardly on shaft 28, after which latches 38 are swung toward cams 52 to secure the door in position and to seal off the chamber opening.

In the specification, I have explained the principles of my invention, and the best mode in 35 which I have contemplated applying those principles, so as to distinguish my invention from other inventions; and I have particularly pointed out and distinctly claimed the part, mode or combination which I claim as my invention or discovery.

While I have shown and described certain preferred embodiments of my invention, it will be understood that modifications and changes may be made without departing from the spirit and 45 scope thereof, as will be clear to those skilled in the art.

I claim:

1. A hinge for a cabinet door comprising a door portion and a cabinet portion, said cabinet portion comprising a bracket attachable to the face of said cabinet, a vertical member rotatably secured on said bracket, a shaft connected to and extending horizontally from said vertical member, a bracket connectible to the side of said door, a pair of outwardly horizontally extending ears on said bracket, apertures in said ears being adapted to slide over said horizontally extending shaft and to be supported thereby, a ring encircling said horizontally extending shaft, said ring being positioned between said ears, and a screw in said ring, said screw being adapted to secure said ring in a desired position on said shaft.

2. A hinge for a cabinet door comprising a bracket, a pair of horizontal members attached 65 to said bracket, a shaft rotating vertically between said horizontal members, a horizontal shaft connected to said vertical shaft, a second bracket, a pair of ears extending perpendicularly from said second bracket, apertures in said ears adapted to engage said horizontal shaft, a ring surrounding said horizontal shaft and positioned between said ears, and a set screw in said ring adapted to fix said ring in a desired position on 70 said shaft.

3. A hinge for a cabinet door comprising a bracket, a pair of horizontal members attached to said bracket, a vertical shaft connected between said horizontal members, a sleeve rotatably mounted around said vertical shaft, a horizontal shaft connected to said sleeve, a second bracket, a pair of ears extending perpendicularly from said bracket and apertures in said ears adapted to engage said horizontal shaft, a thrust bearing between each end of said sleeve and a respective horizontal member, a ring surrounding said horizontal shaft and positioned

between said pair of ears, and screw means for fixing said ring in a desired position upon said horizontal shaft.

JACK SHAMROTH.
